UNITED STATES PATENT OFFICE.

CHAIMSONOVITZ PROSPER ELIESON, OF LONDON, ENGLAND, ASSIGNOR TO THE ELECTRIC LOCOMOTIVE AND POWER COMPANY, (LIMITED,) OF SAME PLACE.

ELECTRICAL ACCUMULATOR OR STORAGE-BATTERY.

SPECIFICATION forming part of Letters Patent No. 358,341, dated February 22, 1887.

Application filed May 18, 1886. Serial No. 202,553. (No model.) Patented in England August 10, 1885, No. 9,522; in Germany October 17, 1885, No. 35,194; in France April 1, 1886, No. 175,193; in Belgium May 12, 1886, No. 73,084; in Luxemburg May 16, 1886, No. 685; in Cape of Good Hope June 24, 1886, No. 6/420, Register No. 356; in Italy June 30, 1886, XX, 19,913, XL, 122; in Victoria July 9, 1886, No. 4,617; in South Australia July 26, 1886, No. 702; in New Zealand July 29, 1886, No. 1,937; in Spain September 1, 1886, No. 1,221/6,023; in New South Wales September 6, 1886, No. 1,919; in Austria-Hungary September 21, 1886, No. 18,560 and No. 47,634, and in India December 6, 1886, No. 1,557, Register No. 112.

To all whom it may concern:

Be it known that I, CHAIMSONOVITZ PROSPER ELIESON, a citizen of the Republic of France, residing at London, England, have invented new and useful Improvements in Electrical Accumulators or Storage-Batteries, (for which I have obtained patents in the following countries, viz: Great Britain by Letters Patent No. 9,522, dated August 10, 1885; in 5 Germany by Letters Patent No. 35,194, dated October 17, 1885; in France by Letters Patent No. 175,193, dated April 1, 1886; in Belgium by Letters Patent No. 73,084, dated May 12, 1886; in Luxemburg by Letters Patent 10 No. 685, dated May 16, 1886; in the Cape of Good Hope by Letters Patent No. 6/420, Register No. 356, dated June 24, 1886; in Italy by Letters Patent XX, No. 19,913, XL, No. 122, dated June 30, 1886; in Victoria by Letters Patent No. 4,617, dated July 9, 1886; in South Australia by Letters Patent No. 702, dated July 26, 1886; in New Zealand by Letters Patent No. 1,937, dated July 29, 1886; in 15 Spain by Letters Patent No. 1,221/6,023, dated September 1, 1886; in New South Wales by Letters of Registration No. 1,919, dated September 6, 1886; in Austria-Hungary by Letters Patent No. 18,560 and No. 47,634, dated September 24, 1886, and in India by Letters Patent 20 No. 1,557, Register No. 112 of 1886, dated December 6, 1886,) of which the following is a specification.

The object of my invention is to improve the construction of electrical accumulators or 25 so-called "secondary batteries" by providing a very large area of acting surface without pasting or otherwise attaching salts of lead to the plates before formation.

In order to enable my invention to be fully 30 understood, I will describe the same by reference to the accompanying drawings, in which—

Figures 1 and 2 represent front and side views, respectively, of an electrical accumulator or storage-battery made according to my

invention, the box or containing-vessel being 45 shown in section.

In constructing an accumulator according to my invention I use a frame, *a*, made ordinarily of lead, which is divided or formed into divisions or compartments *b*, of any suitable 50 shape, the divisions or compartments being shown square in the drawings; but it will be obvious that they may be of any other suitable shape. I take a strip of thin sheet-lead. Upon the said strip I place another strip of 55 sheet-asbestus or other suitable insulating and acid-proof material. I roll up the strips so as to form a compact spiral, *c*, cylindrical in shape. I insert one of these spirals *c* into each compartment or division *b* in the before-men- 60 tioned frame *a*. A series of such frames are arranged in a suitable containing-vessel, *d*, as shown in Fig. 2, and I pass a current through them, forming them in the usual way—that is to say, oxidizing one plate to form + terminal and hydrogenizing the other to form — terminal.

Among the advantages of my improved electrical accumulators may be mentioned, first, that there are no oxides of lead required to be 70 placed therein, which in a crude form are liable to crumble, and by falling between the plates short-circuit the battery; second, that the spiral as constructed according to my invention affords a very large acting surface for 75 electrical storage, whereby such storage may be carried out without adding the unnecessary weight, which constitutes a serious objection against accumulators when used for electrical traction or other kindred applications where 80 the minimum weight against time-storage is a desideratum; third, that such a cell constructed according to my invention increases in capacity during its useful life, which is only short-ened by the disintegration of the leaden frame. 85

In the drawings I have shown the spirals *c* as being of greater length than the thickness of the frames *a*; but such is not necessary, as

the ends of the spirals may be flush therewith.

Having now particularly described and ascertained the nature of my said invention and in what manner the same is to be performed, I

5 declare that what I claim is—

1. An electrical accumulator consisting of a frame of lead or other suitable material, containing spirals of sheet-lead, whose surfaces are separated by suitable insulating and acid-proof
- 10 material, substantially as hereinbefore described.

2. The combination of a containing-vessel, a series of frames inclosed within said vessel, and the spirals *e*, contained within said frame, substantially as hereinbefore described.

C. P. ELIESON.
